UNITED STATES PATENT OFFICE.

WILLIAM K. OMICK, OF PONTIAC, MICHIGAN.

TRIPLE VALVE.

No. 798,619.

Specification of Letters Patent.

Patented Sept. 5, 1905.

Application filed April 23, 1902. Serial No. 104,249.

To all whom it may concern:

Be it known that I, WILLIAM K. OMICK, a citizen of the United States, residing at Pontiac, in the county of Oakland and State of Michigan, have invented certain new and useful Improvements in Triple Valves, of which the following is a full, clear, and exact specification.

This invention relates to triple valves for air-brake systems. Its object is to provide an efficient valve for air-brake systems which shall automatically upon each partial reduction of pressure in the train-pipe open communication between the reservoir and the brake-cylinder and then close the same without shock and upon increase of pressure in the train-pipe shall open communication between the brake-cylinder and exhaust and then close the same.

The invention also includes features of mechanical construction which will be herein-after described.

In the drawings, Figure 1 is a sectional view of a triple valve embodying my invention. Fig. 2 is an end view of the same. Fig. 3 is a detail top view showing the valve-ports and slide-valve plate. Fig. 4 is a detail end view of the slide-valve, showing the manner of its mounting in the valve-plate; and Fig. 5 is a top view of the slide-valve.

Referring more particularly to the drawings, 1 represents the casing, which in this instance comprises a central cylindrical part with two ends bolted thereon. In the side of the casing is fitted the slide-valve plate 2, in which are formed the exhaust-port 3, the brake-cylinder port 4, and the reservoir-port 5. Fitted against the inner side of the valve-plate and sliding thereon is the slide-valve 6. In the construction shown the valve 6 slides in a groove 7 in the valve-plate, as shown in Fig. 4. In the slide 6 are the ports 8 and 9, connected with each other and adapted to register with ports 3 and 4 or 4 and 5. Upon the opposite ends of the slide-valve 6 are formed the legs 10, which straddle and are supported by the stem 11, a spring 12 being interposed between the stem and the slide 6 to hold the valve against its seat. The stem 11 is mounted at the respective ends in the pistons 13 and 14, which are fitted to the walls of the casing and move longitudinally thereof. The pistons 13 and 14 are provided with the flanges 13^a and 14^a for a purpose to be

hereinafter described. At the respective ends 55 of the slide-valve 6 I interpose between the piston and the leg 10 a collar 15 and a packing-disk 16 and upon the opposite side of the piston a washer 17, the whole being clamped against the leg 10 by a nut 18. Nuts 18 being tightened the slide 6 is prevented from moving longitudinally upon the stem and pistons. In the opposite ends of the valve the chambers 19 and 20 are formed by the piston 13 or 14 and walls of the casing, respectively. 60 Chamber 19 communicates with train-pipe 21 and chamber 20 communicates with the atmosphere through port 22, which is opened or closed by the flange 13^a. Chambers 19 and 20 are connected together by a pipe 23. 65 In the present case pipe 23 comprises two sections joined together by a union 24. The openings 25 and 26 from the respective ends of pipe 23 into the chambers 20 and 19 are of small diameter relative to the diameter of the train-pipe 21, thereby permitting a restricted leakage of pressure from one chamber to the other, and thus accordingly equalizing the pressure in the two chambers. The end 27 of the stem 11 projects through the end 28 of the guideway 70 29, formed in the end of the casing, and impinges against the end of the pin 30. Upon pin 30 is formed a shoulder 31, between which shoulder and the inner end 33 of a screw-plug 34 is interposed a spring 32, tending to force the pin 30 outward against the end 28. When the pin is in this position, the stem 11 will hold the slide-valve 6 in lap position, closing all of the ports. When the valve is in this lap or central position, the flanges 80 13^a and 14^a will be in such position that both ports 22 and 26 will be covered by flanges 13^a and 14^a, although port 26 will be nearer the edge of the flange 14^a than port 22 is to the edge of the flange 13^a, and therefore a slight movement of the pistons to the right would uncover port 22, port 26 remaining covered. Movement in the opposite direction would uncover port 26, port 22 remaining covered. This central position is the 90 "running" position of the valve. When a partial sudden reduction of pressure occurs in the train-pipe, bringing this pressure below the pressure trapped in chamber 20, the latter piston will force piston 13 forward, 95 bringing ports 8 and 9 in communication with ports 4 and 5. This opens communication between the reservoir and the brake-cyl-

inder. In moving to this position, however, the flange 14^a will have closed port 26, preventing equalizing of pressure in the chambers, and flange 13^a of piston 13 will have uncovered the port 22, and thereupon the leakage through that port effects a gradual reduction of pressure in the chamber 20. As the pressure in chamber 20 falls below that in chamber 19 the latter pressure moves the piston 14, so that the slide-valve 6 moves back until the stem 27 impinges against the pin 30. The tension of spring 32, together with the fact that port 22 will meanwhile have been closed again, arrests the slide-valve in the lap position, and thus closes all of the ports 3, 4, and 5. If there is not enough pressure upon the brakes, a further partial reduction of pressure in the train-pipe is effected and the same operation as above described again ensues. An emergency application of the brakes is effected by a complete reduction of pressure in the train-pipe. To release the brakes, the pressure in the train-pipe is increased, whereupon piston 14 is moved forward and the stem 27, which impinges against pin 30, compresses the spring 32 until ports 8 and 9 are in communication with ports 3 and 4. Thereupon the brake-cylinder is connected with the exhaust. This movement of piston 14 has, however, first caused flange 13^a to cover port 22 and prevent further release of pressure from chamber 20 and then caused the flange 14^a to uncover the port 26, and thereupon a leakage of pressure from chamber 19 to chamber 20 occurs and gradually continues until the pressure in chambers 19 and 20 is equalized, which permits spring 32 to move the valve back to the lap position, thus shutting off the exhaust. Should the brakes still be partially applied, the pressure will be further increased in the train-pipe, whereupon communication will again be opened between the brake-cylinder and the exhaust and the pressures in chambers 19 and 20 will be again equalized and said communication shut off.

It will be seen that the valve above described effects positively and simply the steady and gentle application and release of the brakes, that there is no loss of air from the brake-cylinder during the application of the brakes, and that but a minimum quantity of air is lost from the train-pipe in operating the valve. Furthermore, by adjusting the tension of the spring 32 and the length of stem 27 and flanges 13^a and 14^a or the area of the ports 25 and 26 the normal position of the valve may be changed at will, and the pressures required for the operation of the valve may also be varied. Therefore it will be understood that I do not herein limit myself to the precise construction or arrangement of the parts or the adjustment thereof shown herein.

It will be understood, of course, that the pressure in the train-pipe will be varied by any of the means already well known.

Having thus described my invention, what I claim as new, and desire to secure by Letters Patent, is—

1. In a triple valve, the combination of a piston, a chamber on each side thereof, a restricted connecting-passage, a train-pipe communicating with one of said chambers the other being normally closed and means for opening the other chamber when the train-pipe pressure is reduced, substantially as described.

2. In a triple valve, the combination of a piston, pressure-chambers on opposite sides thereof, a restricted passage between said chambers, a train-pipe communicating with one of said chambers, and a restricted exhaust-passage from the other chamber to the atmosphere, substantially as described.

3. In a triple valve, the combination of a piston, pressure-chambers on opposite sides thereof, a restricted passage between said chambers, a train-pipe, and means for automatically opening one chamber to the atmosphere and closing said restricted passage upon a reduction of pressure in the train-pipe, substantially as described.

4. In a triple valve, the combination of a piston, pressure-chambers on opposite sides thereof, a restricted passage between said chambers, a train-pipe communicating with one of said chambers, a restricted exhaust-passage from the other chamber to the atmosphere, and means for automatically closing said restricted passage between the chambers upon a reduction of pressure in the train-pipe, substantially as described.

5. In a triple valve, the combination of a piston, pressure-chambers on opposite sides thereof, a restricted passage between said chambers, a train-pipe communicating with one of said chambers, a restricted exhaust-passage from the other chamber to the atmosphere, and means for automatically closing said restricted passage between the chambers and opening the restricted exhaust-passage, upon a reduction of pressure in the train-pipe, substantially as described.

6. In a triple valve, the combination of a piston, pressure-chambers on opposite sides thereof, a restricted passage between said chambers, a train-pipe communicating with one of said chambers, a restricted exhaust-passage from the other chamber to the atmosphere, and means for automatically opening said restricted passage between the chambers and closing the restricted exhaust-passage upon an increase of pressure in the train-pipe, substantially as described.

7. In a triple valve, the combination of a piston, pressure-chambers on opposite sides thereof, a restricted passage between said

- chambers, a train-pipe communicating with one of said chambers, a restricted exhaust-passage from the other chamber to the atmosphere, and means whereby a partial reduction of pressure in the train-pipe effects a closure of said equalizing-passage and a further reduction of pressure effects the opening of said exhaust-passage, substantially as described.
8. In a triple valve, the combination of a piston, pressure-chambers on opposite sides thereof, a restricted passage between said chambers, a train-pipe communicating with one of said chambers, a restricted exhaust-passage from the other chamber to the atmosphere, and means whereby a partial increase of pressure in the train-pipe effects a closure of said exhaust-passage and further increase of pressure effects an opening of said equalizing-passage, substantially as described.
9. In a triple valve, the combination of a piston, pressure-chambers on opposite sides thereof, a spring normally holding the piston in lap position when the pressure in the chambers is equalized, an equalizing-passage between the chambers, and means for effecting a difference in pressure between the chambers by opening one of them to the atmosphere, substantially as described.
10. In a triple valve, the combination of a piston and chamber on each side thereof, a restricted connecting-passage, a train-pipe communicating with one of said chambers, said piston opening the other chamber to the atmosphere when the train-pipe pressure is reduced, substantially as described.
11. In a triple valve, the combination of a cylindrical casing, ends thereof a piston moving longitudinally therein, and forming chambers in opposite sides thereof, an equalizing-passage between said chambers, means for opening one of them to the atmosphere and a flange carried by said piston and adapted to control said passage, substantially as described.
12. In a triple valve, the combination of a cylindrical casing having closed ends, a double piston moving in said casing and forming chambers in the opposite ends of the casing, a slide-valve carried by said piston, a train-pipe communicating with one of said chambers, and an equalizing-pipe between the chambers, one of said chambers opening to the atmosphere, substantially as described.
13. In a triple valve, the combination of a cylindrical casing having closed ends, a double piston moving in said casing and forming chambers in the opposite ends of the casing, a slide-valve carried by said piston, a train-pipe communicating with one of said chambers, a spring normally holding the slide in lap position, and a restricted passage between the two chambers, substantially as described.
14. In a triple valve, the combination of a piston, a chamber on each side thereof, a restricted connecting-passage, a train-pipe communicating with one of said chambers, said piston opening the other chamber to the atmosphere and closing the connecting-passage when the train-pipe pressure is reduced, substantially as described.
15. In a triple valve, the combination of a piston, a chamber on each side thereof, a restricted passage, a train-pipe communicating with one of said chambers and means for automatically reducing the pressure in the other chamber after the brakes have been applied, substantially as described.
